DESIGN FOR A LUBRICANT DISPENSING APPARATUS OR SIMILAR ARTICLE

Harold Van Doren and John McLeod Little,
Toledo, Ohio, assignors to The Aro Equipment Corporation, Bryan, Ohio, a corporation of Ohio

Application April 5, 1937, Serial No. 68,570

Term of patent 7 years

To all whom it may concern:

Be it known that we, Harold Van Doren and John McLeod Little, citizens of the United States and residents of Toledo, in the county of Lucas and State of Ohio, have invented a new, original, and ornamental Design for a Lubricant Dispensing Apparatus or Similar Article, of which the following is a specification, reference being had to the accompanying drawing, forming part thereof.

Figure 1 is a perspective view of a lubricant dispensing apparatus or similar article showing our new design.

Figure 2 is a top plan view of the pump, with the dotted line illustration of Figure 1 omitted.

Figure 3 is a side elevational view thereof; and

Figure 4 is a side elevational view at right angles to the view shown in Figure 3.

The dominant features of our design reside in portions shown in full lines.

We claim:

The ornamental design for a lubricant dispensing apparatus or similar article as shown and described.

HAROLD VAN DOREN.
